PROCESS FOR HEATING DECOMPOSABLE MATERIALS

Filed June 11, 1927

FIG.-II

FIG.-1

JACKSON R. SCHONBERG, Inventor

By his Attorney, C. H. Straw.

UNITED STATES PATENT OFFICE

JACKSON R. SCHONBERG, OF WESTFIELD, NEW JERSEY, ASSIGNOR TO STANDARD OIL DEVELOPMENT COMPANY, A CORPORATION OF DELAWARE

PROCESS FOR HEATING DECOMPOSABLE MATERIALS

Application filed June 11, 1927. Serial No. 198,134.

The present invention relates to the art of heating fluids by combustion gases and more specifically comprises an efficient method for the distribution of heat in furnaces to prevent local over-heating and at the same time to use fuel economically. My method and apparatus therefor will be fully understood from the following description and the attached drawings referred to in the same.

- 16 In the heating of fluids which are sensitive to excessive temperatures, such as oils and the like, there has been great difficulty in obtaining efficient combustion. If the excess air, as indicated by flue gas analysis, is kept 20 low, the temperature in the zone of combustion will be high and radiation from the flames and the inner walls of the furnace is often injurious to the heating surface and the material being heated. In oil heating equipment this is especially troublesome since over-heating of the oil causes a deposition of coky material on the heating surface and the still may be seriously damaged.

The condition above described is generally met by allowing a large excess of air to enter the combustion zone with the result that the temperature therein is lowered to a point at which the radiation is not sufficiently intense to cause over-heating, but fuel efficiency suffers in consequence as will be well understood.

It is a well known fact that certain gases, notably steam and carbon dioxide, are semi-opaque to heat rays. The expression semi-opaque means that a certain proportion of heat passing by radiation into a layer of gas is absorbed by the gas itself, depending on the thickness of the layer and the nature of the gas, so that only a certain fraction of the 40 radiation passes through and leaves the gas layer. My invention consists in maintaining a layer or bank of such a semi-opaque gas between the radiating elements and the still surface. A part of the heat passes directly 45 through the gas layer and is absorbed by the metal surface while the remainder is absorbed by the gas layer. As the gas becomes heated it may be drawn off and utilized in another part of the furnace.

50 Referring to the drawings, Fig. I is a ver-

tical elevation in section of a pipe still heating coil constructed according to my invention and,

Fig. II shows a shell type oil still, adapted for operation of my process.

The pipe still heating coil shown in Fig. I is made up of two sections or heating zones, the combustion zone being indicated by the character 1 and the convection or preheating zone by the numeral 2. A wall 3 separates the two zones but holes 4 through the wall 3, preferably near the furnace floor 5, allow passage of combustion gases from the fire box to the convection section. Burners 6 project into the combustion section in the usual manner and flue gas is withdrawn from the furnace by the stack 7 which is fitted with damper 8.

In section 1 the heating surface 9, in the form of parallel tubes, is placed well above the furnace floor and the height above the burner level is sufficient so that a bank or layer of a semi-opaque gas may be maintained between the burner level and the heating surface. The semi-opaque gas may be admitted by pipes 10 above burners 6. The top of the combustion chamber is sealed so that the only escape for combustion gas is through holes 4, which are close to the floor level, preferably in alignment with the burners 6, and by this means the layer of semi-opaque gas may be maintained with little tendency for hot gas from the flames sweeping up around the tubes 9. Additional heating surface 11 is distributed throughout the section 2 in order that the temperature of the flue gas may be reduced to an economical degree before discharge to the stack. The semi-opaque gas is drawn from any convenient source not shown in Fig. 1 and, after discharge from the fire box. It is mixed with the combustion gases and flows through section 2. The oil is pumped first through the convection section where it is preheated and through the combustion section as indicated by the arrows, or in any other suitable manner, and is finally discharged to a vaporizing drum or tower not shown in Fig. 1.

In Fig. II my invention is applied to a crude or rerun still of the shell type. As in

Fig. I, the character 1 designates the combustion chamber and numeral 2' again refers to the convection chamber. In this case, however, the combustion chamber consists of 5 a number of flues extending from end to end of the still. The other elements are numbered as in Fig. I. The shell 9' is protected by the semi-opaque gas admitted by line 10 above burners 6. A fan or blower 13 draws 10 flue gas, containing steam and CO₂, from flue 12 and for use as a part of that making up the layer injected at 10. The other part of the flue gas passes from flue 12 into stack 7. The other elements of the still such as charging line, vapor line and tar draw-off are indicated by 13', 14 and 15 respectively.

In the operation of my process the semi-opaque gas is interposed as a thick bank or layer between the still surface and those elements 20 from which the intensity of radiation is high. The thickness of the gas layer and the nature of the gas determine the quantity of heat absorbed in the combustion section and regulation of the heat absorption may 25 be maintained by control of the flow of interposed gas and by its composition. It is important to keep the layer of gas intact as well as possible so that the construction of the back wall 3 should be as described. It has 30 been found that, when burning fuel with about 20% excess air and heating oil to a temperature in excess of 750° F., a layer of from 1 to 3 ft. in thickness and containing about 11% CO₂ and 12% H₂O was sufficient 35 to protect the tubes from over-heating.

While my invention has been described in reference to heating oil, it should be understood that the process is applicable to the heating of any fluid sensitive to over-heating. 40 My invention is not to be limited by any theory of the mechanism or by any example given in the way of illustration. I wish to be limited only by the following claims, in which I claim all novelty inherent in my invention.

45 It is pointed out that the term "source of radiation" used in the claims includes both solid radiating surfaces such as highly heated furnace walls and the layer of hot combustion gases.

50 I claim:

1. The method for protecting heat absorption surfaces of a still from local over-heating by radiation, comprising maintaining 55 a relatively cool layer of a semi-opaque gas between such surfaces and the source of radiation.

2. The method for protecting heat absorption surfaces of a still against local over-heating due to radiation, comprising flowing a 60 layer of relatively cool semi-opaque gas between the heat absorption surfaces and the source of radiation.

65 3. The method for protecting heat absorption surfaces of an oil still against local over-

heating due to excessive radiation comprising keeping the flames and highly heated gas out of contact with the heating surface and tempering the intensity of radiation by interposing a layer of relatively cool, semi-opaque gas between the source of radiation and the heating surface.

4. The method for economically heating fluid sensitive to excessive temperatures comprising burning fuel with relatively small 70 excess of air in a radiation zone, interposing a layer of semi-opaque gas between the flames and heating surfaces containing the fluid to be heated, withdrawing and mixing the gases from the radiation zone, passing the same 75 to a second heating zone and absorbing heat 80 from said gases therein.

5. A method according to claim 3, in which the semi-opaque gas is at least one foot in thickness and contains substantially equal 85 parts of carbon dioxide and water vapor.

JACKSON R. SCHONBERG.
